PUMPING JACK

Samuel C. Kyle, Berkeley, Calif., assignor to The Pelton Water Wheel Company, San Francisco, Calif., a corporation of California

Application December 4, 1946, Serial No. 713,890

5 Claims. (Cl. 121—158)

1

The invention relates to pumping jacks especially for use in extracting oil from wells which are of necessity pumped and is particularly concerned with a pumping jack of the type shown in the co-pending application of Fred H. Rued, Serial No. 667,717, filed May 6, 1946, now Patent Number 2,481,623, and entitled "Pumping Jack." The Rued application is assigned to the assignee of the present application.

In a pumping jack of this character there is provided a cylinder usually arranged vertically over the well and within which operates a piston connected through its piston rod to the polished or sucker rod of the pump which is disposed at a depth within the well. The pumping jack piston is raised and lowered in a carefully regulated fashion by means of an actuating fluid, usually oil, pumped into and out of the jack cylinder under the driving force of an engine or motor and precisely controlled so that the well pump is appropriately stroked and so that the rate of pumping desired is maintained for protracted periods.

In the operation of a pumping jack of this kind the viscosity and some of the other characteristics of the actuating fluid vary from summer to winter and furthermore there are some variations in the length of the sucker rod in any given well or in successive wells in the event the same jack is utilized repeatedly on different installations. The variabilities mentioned are difficulties to be overcome in the design and operation of a universally applicable pumping jack.

It has been proposed heretofore, as shown in the Rued application, to provide a conduit extending from the jack cylinder at one side of or beneath the piston for conducting the pressure existing in the cylinder to a control valve for regulating the piston stroke. It has also been customary to employ a check valve for the purpose of preventing retrograde flow in such conduit, but considerable difficulty has resulted in practice due to a surge or hammer occurring in that conduit due to the sudden imposition on the conduit and check valve of a relatively high pressure. This has rendered the operation of the check valve erratic and especially has rendered the operation of the control valve erratic. This condition is likely to result in a failure of the piston arresting mechanism so that the piston can upon occasion overtravel sufficiently to cause mechanical damage not only to the pumping jack, but more seriously to the pump itself.

It is therefore an object of the invention to provide means for regulating the length of stroke

2

in a pumping jack to compensate for variations in actuating fluid viscosity especially those due to the seasons.

It is another object of the invention to provide a means of adjusting or regulating a pumping jack to cooperate properly with the particular pump with which it happens to be installed at any time.

Another object of the invention is to provide means of avoiding or preventing hammer or surge in a control line.

An additional object of the invention is to provide means for preventing chattering or erratic operation of a check valve or control valve actuated by the hydraulic jack itself.

An additional object of the invention is to provide means for precluding damage to the pump and if possible to the pumping jack itself in the event the control structure fails to arrest the motion of the piston adjacent one end of its stroke.

Other objects of the invention together with the foregoing are attained in the embodiment of the invention disclosed in the accompanying drawings in which

Figure 1 is a diagrammatic disclosure of a pumping jack constructed to incorporate the present invention, certain portions of the diagram bearing legends so that it can be compared with the drawings in the copending application of Rued above identified.

Figure 2 is a cross section showing in detail a check and stop valve and connections utilized in connection with the structure of Figure 1.

Figure 3 is a cross section on a central or axial plane showing the interior construction of the pumping jack cylinder and piston adjacent one end thereof, the structure being that diagrammatically shown near the bottom of Figure 1.

In its preferred form, the pumping jack of my invention incorporates a cylinder having a piston reciprocable therein under the influence of an actuating fluid admitted to the cylinder to one side of the piston and incorporates a plurality of branch pipes communicating with the cylinder at selected, spaced locations traversed by the piston and merging into a pipe extending to a control valve for regulating the stroke of the piston. Included in the branch pipes are check valves for preventing flow of pressure fluid from the cylinder toward the control valve and also operable to block or to prevent flow in either direction between the cylinder and control valve. Further, there is included a means for utilizing the cylinder and piston structure as a dash pot

with a predetermined leakage therefrom to arrest the descent of the piston in the event of an emergency.

While the pumping jack arrangement in accordance with my invention can be made in a number of different ways and can be incorporated with structures other than pumps, it has found a satisfactory commercial embodiment as shown herein. There is provided a pumping jack cylinder 6 of considerable vertical extent having a base frame 7 connected by struts 8 to a suitable support on and surrounding a well bore (not shown). The base 7 includes a packing structure 9 surrounding a piston rod 11 extending downwardly into the well where it is connected to a pump in the customary fashion. At its upper end, the rod 11 is connected to a piston 12 reciprocable within the cylinder 6 and at its lower end provided with a reentrant portion defining a cavity 13. A restricted passageway 14 is afforded by a bore through the side wall of the piston and establishes communication between the cavity 13 and the exterior of the piston when the bore is in line with a port 16 formed in the base 7. The port 16 is connected to a conduit 17 extending to a main valve 18 effective to control the ingress of actuating fluid to the cylinder 6 on one side of or below the piston 12 and in timed relationship to control the egress of the actuating fluid from the cylinder 6. With the timed ingress to and egress from the cylinder 6 of the actuating fluid, the piston 12 rises and falls together with the rod 11. In the event of failure of any of the control instrumentalities which regulate the operation of the piston, and in any event when the entire weight of the pump and rod structure is suddenly imposed upon the piston 12 without the customary regulation, the piston descends until its lower edge 18 overrides the port 16 thereby trapping a quantity of the working fluid in the cavity 13. The piston and connections are immediately arrested and can descend to the bottom no faster than is permitted by the expulsion of the working fluid at a predetermined rate through the passage 14. This is so slowly that no damage can ensue to the structure.

For normal operation, the regulating mechanisms create an alternate flow of actuating fluid into and out of the cylinder so that the piston 12 rises and falls with a regular rhythm. Above the piston, the cylinder 6 is provided with an overflow or discharge chamber 21 of an enlarged form opening into the cylinder 6 through apertures 22 in order to preclude undue compression above the piston of atmospheric air. The chamber 21 is in communication through a conduit 23 with a scavenge pump or scavenge chamber (not shown) there being provided a check valve 24 affording flow in the direction of the arrow indicated thereon, that is, in a direction away from or out of the cylinder 6 and precluding any return flow.

To regulate the upper limit of the piston stroke a plurality of pipes such as 26 intersect the cylinder 6 at a plurality of selected locations affording a plurality of ports such as 27. The various pipes 26 all merge with a regulating valve casing 28 having a rotor 29 therein. A bore 31 traverses the rotor and always is in communication with a chamber 32 so that when the valve 29 is rotated into any one of its selected positions the corresponding one of the ports 27 is placed in communication with a pipe 33. This leads to a conduit 34 communicating with a control valve explained in detail in the mentioned Rued patent

and in general is effective to regulate the flow of actuating fluid into and out of the cylinder 6. A check valve 36 is interposed in the line between the pipes 33 and 34 to permit flow away from the cylinder toward the control valve but to prevent return flow therefrom. When the piston 12 is lifted by the pressure actuating fluid above the one of the ports 27 that has been selected by the valve 29, the pressure of the fluid is then communicated through the pipe 26, the valve 29 and the check valve 36 to the control valve to reverse the operation of the structure. By manipulating the valve 29 properly the desired height of stroke can be obtained.

In a somewhat comparable fashion I provide in accordance with my invention a plurality of ports 41, 42, 43, 44, and 45 at convenient, selected locations in the cylinder 6. All of the ports are traversed by the piston 12 and each of them is provided with one of a plurality of pipes 47, 48, 49, 50 and 51 all of which merge into a pipe 53. This latter pipe establishes communication with a pipe 54 extending to the control valve 55 for regulating the flow of actuating fluid into and out of the cylinder 6 through the port 16. For convenience all of the pipes 47, 48, 49, 50 and 51, as well as the pipes 53 and 54 are referred to collectively herein as a "conduit."

In accordance with the invention each of the pipes, for example the pipe 47, is provided with a special check valve such as the valve designated 56. The valve includes a valve body 61 (Figure 2) having a central cylindrical bore 62 within which a valve thimble 63 is slidably disposed. The valve thimble intermediate its ends has a poppet head 64 engageable with a poppet seat 65 in the valve body. When seated, the thimble precludes flow past the seat. Normally the thimble is urged onto the seat by a coil spring 66 surrounding an extended stem 67 on the thimble and likewise in abutment with a plug 68 screwed into the threaded end 69 of the valve body.

The valve thimble is centrally provided with a bore 71 from which a plurality of passages 72 established communication between the interior of the valve thimble and the exterior thereof when the valve is unseated against the compressive urgency of the spring 66.

Extending into one side of the valve body 61 above or to one side of the seat 65 is a short nipple 73 also screwed into the cylinder 6 in communication with the port 41, for example, and setting up communication between such cylinder and the interior chamber 74 on one side of the valve seat 65. The nipple 73 constitutes or represents the pipe 47. Likewise screwed into the valve body 61 are fittings 76 and 77 included in or portions of the pipe 53.

In the operation of the structure as so far described, when the piston 12 rises above the port 41 for example, pressure fluid exerts its force through the pipe 47 (represented by the nipple 73) and imposes a force upon the head 64 of the check valve to augment the pressure of the spring 66 so that the valve is held seated and communication therethrough is precluded. However when the piston 12 descends below the port 41 and permits atmospheric or a relatively low pressure from the chamber 21 or from the conduit 23 to be imposed through the pipe 47 (the nipple 73) upon the spring side of the check valve, then the pressure fluid already present in the conduit 54 is effective to unseat the check valve against the urgency of the spring. The

resulting sudden reduction of pressure in the control valve conduit 54 is effective to actuate the control instrumentalities and reverse the previous flow direction of the actuating fluid. The result is that the piston no longer descends but rather is again supplied on its under side with actuating fluid and is again lifted. By this means the check valve is effective in the structure to regulate the bottom stroke limit of the jack piston. It is emphasized that the check valve is installed in the conduit extending to the control valve at a location as close as possible to the cylinder port such as the port 41. That is, the nipple 73 is a short pipe so that pressure variations therein are not effective to set up surges or "water hammer" or similar violent phenomena and consequently the control valve operates smoothly. Previously, fluid surge in the control conduit produced sundry difficulties. In accordance with the present invention the check valve is installed close to the main cylinder so that violent surging is precluded.

Also in accordance with the invention, I provide means for selecting any one of the ports for operation while precluding operation of the remaining ones. The blocking means for preventing operation of the various ports 41, 42, 43, 44 and 45 can take any suitable form such as an additional valve, but preferably I utilize the check valve shown in Figure 2 and add to it a threaded stem 81 engaging the plug 68 and rotatable by means of a tool engaged with an end slot 82 to approach the head 67 of the check valve. The stem 81 not only regulates the extent of opening of the check valve, but if sufficiently actuated is effective forcibly to hold the check valve on its seat thus to preclude fluid flow therethrough in either direction. The stem 81 when in appropriate position is locked by a nut 83 jammed against the plug 68 and also by a cap nut 84 for sealing the structure against tampering.

With the structure described, any one of the check valves 56 can be opened to afford unidirectional flow without surge or water hammer and thereby to select the point of reversal or bottom stroke limit of the piston 12 in accordance with whichever port 41, 42 etc. is opened by such operation. The other or non-selected check valves are held completely closed by a suitable adjustment of the stem 81 so that the structure is set for the stroke operation desired. With this arrangement, stroke changes can be made periodically throughout the season to take care of variations between summer and winter fluid viscosity. Also there can be established appropriate adjustments if or when the pumping jack is moved from one installation to another. Furthermore, the installation is such that water hammer or surging or chatter is prevented and not only does the acting check valve have a long life but the control valve is provided with a smooth impulse and not a repetitive deleterious one. Finally, in the event of failure of the structure to act as a bottom limit of the stroke, the mechanism is not damaged because the dash pot effect of the piston and cylinder at the bot-

tom is effective gradually to permit the structure to come to mechanical rest.

I claim:

5. A pumping jack comprising a cylinder, a piston reciprocable in said cylinder, means for supplying said cylinder with actuating fluid, a hydraulically actuated control valve for said supplying means, a relatively long hydraulic actuation conduit extending between said cylinder and said control valve, and a check valve closed by flow of actuating fluid from said cylinder disposed in said conduit between said cylinder and said valve and located close to said cylinder.
